BOAT WHEELING ATTACHMENT
Jerry W. Raymond, 1102 Crescent St.,
Wenatchee, Wash. 98801
Filed June 14, 1965, Ser. No. 463,774
5 Claims. (Cl. 280—47.32)

ABSTRACT OF THE DISCLOSURE

Clamps onto a side or the rear transom of an upside down boat. The clamp has one non-movable and one movable clamp plate. Two L-shaped clamp brackets are secured to the non-movable clamp plate. Two clamp screws are threaded through the brackets and the movable clamp plate is carried by the inner end of these screws. The upper end of a fork is rigidly but adjustably secured to the non-movable clamp plate and a wheel is journaled in this fork.

My invention relates to a boat wheeling attachment which is quickly and easily attached to and detached from a small boat to make possible easy movement of the boat on land and an object of my present invention is to improve and simplify the construction of boat wheeling attachments of the general type disclosed in my two prior Patents No. 3,101,230 and No. 3,159,410.

In applying boat wheeling devices to small boats it is usually desirable to turn the boat upside down and attach the wheeling devices either to the side walls or to the rear end wall or transom of the boat. The inclines or angles of the walls of small boats are not uniform but said walls are flared and curved and inclined at various angles and an object of this invention is to provide a boat wheeling attachment which is universally applicable to substantially all small boats regardless of the shape and incline of the walls and regardless of whether it is applied to longitudinally extending side walls or to transversely extending rear or transom walls.

Another object of my invention is to provide a boat wheeling attachment comprising a wheel rotatively mounted in a wheel bracket or fork and a clamp member connected with said wheel bracket in such a manner that it can be adjusted about two axes at right angles to each other, one axis of adjustment normally being generally upright and the other axis normally being generally horizontal when the wheeling attachment is applied to and supporting a boat, said two axes of adjustment making it possible, while keeping the wheel in a substantially vertical plane which is generally parallel to the longitudinal axis of the boat, to apply the clamp to differently positioned and differently inclined side walls and end walls of the boat.

Other objects of my invention will be apparent from the following description taken in connection with the accompanying drawings.

FIGURE 1 is a view in elevation of my boat wheeling attachment showing the same attached to the side of a boat, a fragment of the boat being shown in section.

FIG. 2 is a side view looking in the direction indicated by broken line 2—2 of FIG. 1, the side of the boat being omitted.

FIG. 3 is a view similar to FIG. 1 showing the clamp part of the attachment adjusted to a different position and applied to the boat in a different manner than it is in FIG. 1.

FIG. 4 is a fragmentary sectional view taken substantially on broken line 4—4 of FIG. 2 but with the clamp and fork parts of the attachment adjusted, rela-

2

tive to each other, into a different position from the position in which they are shown in FIGS. 1, 2 and 3.

FIG. 5 is a fragmentary view, with parts in section, looking in the direction indicated by broken line 5—5 of FIG. 4.

FIG. 6 is a somewhat diagrammatic fragmentary side elevation, on a reduced scale, showing one of my attachments applied to the transom of a boat.

FIG. 7 is a view similar to FIG. 6 showing the attachment applied to the side wall of a boat.

FIG. 8 is a view in elevation showing a modified and simplified form of my boat wheeling attachment.

FIG. 9 is a view in elevation looking in the direction indicated by broken line 9—9 of FIG. 8.

FIG. 10 is a view partly in elevation and partly in section taken substantially on broken line 10—10 of FIG. 9.

FIG. 11 is a perspective view of an adapter board capable of use with my boat wheeling attachment to make possible application of the attachment to a boat in a right side up position.

FIG. 12 is a somewhat diagrammatic reduced scale view illustrative of the use of said adapter board in applying my boat wheeling attachment to a boat in a right side up position.

Like reference numerals indicate like parts throughout the several views.

The boat wheeling attachment shown in FIGS. 1 to 7 and 12 comprises a flat rectangular metal frame plate 20 having the edge portion thereof which is shown lowermost in FIGS. 1 to 4 bent at right angles to form a flange 21. Two parallel spaced apart clamp brackets 22 and 23, of the type commonly called C-clamps, are welded or otherwise rigidly secured to the flange 21 and are positioned near the respective lateral edges of the base plate 20 in planes perpendicular to the plane of said base plate 20. Two clamp screws 24 and 25 are threaded through the terminal portions of the outermost arms of the respective clamp brackets 22 and 23. The usual transverse slidable bar-type hand hold members 26 are provided in the outer end portions of the clamp screws 24 and 25. The inner ends of both clamp screws 24 and 25 are permanently connected, by suitable attachment members 27, with a flat clamping plate 29. The members 27 provide a loose connection between the screws 24 and 25 and the clamping plate 29 so that said clamping plate is self adjusting, within reasonable limits and will lie flatly against surfaces of varying incline to which it is applied.

A flat wood block 30 of substantial thickness is secured as by screws 37, FIG. 4, to the frame plate 20 and provides a surface which can be clamped against a part of a boat without objectionably marring the part against which it is clamped. The edge of the block 30 nearest the flange 21 is spaced a substantial distance from said flange 21 to provide a recess 31 for the reception of the gunwale portion of a boat, as hereinafter explained.

Two axially aligned, spaced apart tubular members 32 are welded or otherwise rigidly secured to the external corner portion of the frame formed by plate 20 and flange 21 with the axis common to said tubular members 32 offset transversely relative to the plane of the outer surface of the frame plate 20, for reasons hereinafter explained. A nut 33, which serves as an internally threaded boss, is welded to the outer side of each tubular member 32 and a set screw 34, preferably of recessed head type, is threaded through each nut 33 and extends through a suitable hole in the tubular member 32 and can be jammed against a cylindrical rod 35 which extends through both tubular members 32. The set screws 34 lock the tubular members 32 and rod 35 together and at the same time allow for relative rotative adjustment of said tubular members 32 and rod 35. Preferably a reinforcing plate or gusset 36 is welded between each tubular member

32 and the frame plate 20. This gusset 32 can also be welded to the adjacent nut 33.

A fork mounting member composed of two tubes 39 and 40 is adjustably supported from the rod 35. The two tubes 39 and 40 are rigidly attached together in relatively crossed relation at right angles to each other and the normally upright tube 39 is longer than the normally horizontal tube 40. Said shorter tube 40 is mounted on the rod 35 between the two tubular members 32 and is rigidly secured to said rod 35, see FIG. 4, by a screw 41 which is threaded through a nut 42 that is welded to and forms a rigid boss on the tube 40 and seats in a suitable indentation in the rod 35.

The longer, normally upright tube 39 adjustably supports a fork. The fork comprises two side by side parallel wheel mounting bars 43 having their upper end portions rigidly connected with each other by a cross member 44 and having an upwardly extending shank 45 rigid with said cross member 44 and received within the tube 39. Preferably the shank 45, FIG. 4, extends through a suitable hole in the cross member 44 and is welded to said cross member by weld 48. Screws 46, preferably two in number, are threaded through nuts 47 which are welded to and form bosses rigid with the tube 39. These screws 46 serve as means for adjustably locking the shank 45 to the tube 39. A wheel 49 is rotatively supported by the bars 43.

In the use of the boat wheeling attachment shown in FIGS. 1 to 7 one of the devices can be attached to the rear end wall or transom T of a boat B, as shown in FIG. 6, with the boat in an up side down position and the boat can easily be wheeled and balanced by one person who supports the forward end of the boat and moves it as desired. When one of my attachments is thus applied to the transom T of a boat the frame plate 20 will be parallel to the transom T and the wheel 49 will be positioned so that it is in a plane generally parallel to the length of the boat and at right angles to the plane of the frame plate 20 and transom T.

The shapes and inclines of the sides of boats vary widely in different boats and at different locations in the same boats and the provision for relative adjustment of the two parts of my device about two different axes at substantially right angles to each other, that is about the axis of the rod 35 and the axis of the fork shank 45, makes it possible to apply two of these wheeling attachments at almost any desired location to the respective side walls of substantially any small boat with the wheels 49 of each device correctly positioned in an upright plane parallel to the length of the boat for most efficient operation.

FIGS. 1 and 3 and FIG. 7 show one of my attachments applied to an inclined side wall 51 of a boat. In FIGS. 1 and 7 the clamp screws are on the outer side of the boat and in FIG. 3 they are in engagement with the inner surface of the side wall 51. In both FIG. 1 and FIG. 3 the clamp and fork parts are adjusted relative to each other so the wheel 49 stands in a vertical plane parallel to the length of the boat. Positioning the axis of the rod 35 outwardly from the plane of the frame plate 20 allows for the relative angular adjustment between the fork means and the clamp means as shown in FIG. 1. If the attachment shown in FIGS. 1 to 7 is to be applied to a boat in a right side up position then it is used in connection with an adapter board 60 of the form shown in FIGS. 11 and 12 and hereinafter described.

FIGS. 8, 9 and 10 show a modified and simplified form of my invention in which the parts 20 to 31 inclusive of a clamp and the parts 43, 44 and 45 of a fork member, carrying a wheel 49, are duplicates of those shown in FIGS. 1 to 7 and are similarly numbered. In this modified form of the attachment the means which makes possible relative adjustment of the clamp part and the fork part on the normally horizontal axis which is provided by the rod 35 of FIGS. 1 to 7 is omitted and a tubular

member 55 is welded or otherwise rigidly secured to the outer side of the frame plate 20. The tubular member 55 is positioned mid way between the two lateral edges of the frame plate 20 and is perpendicular to the flange 21. At least one and preferably two set screws 56, each threaded through a rigidly attached nut 57, which forms a boss, are provided to lock the fork shank 45 against rotation in the tubular member 55.

The clamp of FIGS. 8, 9 and 10 can be applied to the transom or to the side walls of a boat in the manner previously described and the fork member adjusted so that the wheel 49 is in a plane generally parallel to the length of the boat for either transom or side wall application of the attachment. If the attachment is applied to a flared side wall the wheel 49 will not stand vertical but will be substantially parallel to the side wall and can be used in this way.

The application of either form of boat wheeling attachment herein disclosed to a small boat B, FIG. 12, in a right side up position is made possible by providing an adapter member or plate in the form of a fairly strong board 60, FIG. 11, in the order of two feet long and eight inches wide. One end portion of a boat B in a right side up position may be supported from the gunwale strips 52 on either its side walls or its transom by placing the upper ends of two boards 60, if applied to the side walls, or either one or two boards 60, if applied to the transom, under the gunwale strips 52, applying at least one and preferably two C-clamps 61 to the upper end portion of each board 60 and the wall of the boat against which it lies to hold the board in place and applying a wheeling attachment to the lower end of each board. Preferably the upper end portion of each board 60 has spaced apart longitudinal slots or saw cuts 62 therein to render it more flexible in transverse directions so it will be more conformable to the longitudinal curvature of curved boat sides and can be clamped more tightly against them. Also preferably two spaced apart parallel strips 63 are secured to the side of the board 60 which is normally innermost near the lower end of said board and adjacent the lateral edges of the board. The strips receive therebetween either the clamping block 30 or the frame plate 20, it being understood that the clamping block 30 can be omitted. Also preferably a thin layer 64 of flexible waterproof plywood is permanently secured by waterproof glue to the outermost side of the board 60 and two hook like members 65 each having end members 66 which hook over the gunwale strips 52 are adjustably secured to the board 60 by bolts 69 which extend through longitudinal slots 67 in the members 65 for adjustment of said members 65. An end portion of one member 65 is broken away in FIG. 11.

Two of the attachments illustrated in FIGS. 1 to 7 are shown in FIG. 12 but it will be understood that the attachment shown in FIGS. 8, 9 and 10 may be used with the boards 60 in a similar manner.

The foregoing description and accompanying drawings clearly disclose preferred embodiments of my invention but it will be understood that changes may be made within the spirit of this disclosure and the scope of the following claims.

I claim:

1. A readily attachable and detachable boat wheeling attachment comprising a fork member; a wheel rotatively mounted in said fork member; an upwardly extending axial shank on said fork member; a tubular member rotatively receiving said shank; a frame plate positioned along side of and secured to said tubular member; two parallel spaced apart clamp brackets rigid with said frame plate and extending outwardly from an edge of the frame plate and back over the frame plate in spaced relation from said frame plate, said tubular member being positioned approximately mid way between said two clamp brackets; a clamp screw threaded through the terminal portion of each clamp bracket and extending toward the

frame plate; and a clamping plate carried by the two clamp screws and extending across the frame plate, the rotative adjustment of said shank in said fork mounting member making it possible to adjust the angular position of the wheel relative to the bracket for selective application of the wheeling device to either side wall or to the rear transom of a boat.

2. A readily attachable and detachable boat wheeling attachment comprising a fork member; a wheel rotatively mounted in said fork member; an upwardly extending axial shank on said fork member; a tubular member adapted to receive said shank; means operable to lock said shank and said tubular member together in different positions of rotative adjustment relative to each other; a frame plate positioned alongside of and secured to said tubular member; an edge flange perpendicular to and rigid with and extending across the end of said frame plate nearest said fork member means positioned adjacent said flange adjustably attaching said tubular shank receiving member to said frame plate, said means providing for tilting adjustment of said tubular shank receiving member toward and away from the frame plate; two parallel spaced apart clamp brackets rigid with and extending outwardly from the frame plate and flange across the flange and back over the frame plate in spaced relation from the frame plate; a clamp screw threaded through the terminal portion of each clamp bracket and extending toward the frame plate; and a clamp plate loosely connected with the inner ends of the two clamp screws and extending across the frame plate in opposed clamping relation to the frame plate.

3. The apparatus as claimed in claim 2 in which a non-metallic face plate of substantial thickness is secured to said frame plate on the side thereof facing said clamp screws, the edge of said face plate adjacent said flange being spaced a substantial distance outwardly from said flange thereby providing a gunwale receiving recess between the flange and the adjacent edge of the face plate.

4. A readily attachable and detachable boat wheeling attachment comprising a fork member; a wheel rotatively mounted in said fork member; an upwardly extending axial shank on said fork member; a tubular member adjustably receiving said shank; means operable to lock

said shank and said tubular member together in different positions of rotative adjustment relative to each other; a frame plate positioned alongside of said tubular member; an edge flange perpendicular to and rigid with and extending across the end of said frame plate nearest said fork member, said frame plate and edge flange forming a corner at the location where they are joined; a mounting rod extending across and rotatively adjustably secured to said frame plate and flange adjacent and parallel to said corner; means rigidly securing said tubular member to said mounting rod with the tubular member extending across said mounting rod approximately at right angles thereto, whereby adjustment is provided between said frame plate and flange and said fork member about two axes approximately at right angles to each other; two parallel spaced apart clamp brackets extending outwardly from the frame plate across the flange and back over the frame plate in spaced relation from the frame plate; a clamp screw threaded through the terminal portion of each clamp bracket and extending toward the frame plate; and a clamp plate connected with the inner ends of the two clamp screws and extending across the frame plate.

5. The apparatus as claimed in claim 4 in which two spaced apart mounting rod supporting tubes are rigidly secured to the frame plate and flange and rotatively adjustably support said mounting rod and in which said mounting rod extends through and is rigidly attached to a cross tube which is rigidly secured to and extends crosswise of the tubular member.
